UNITED STATES PATENT OFFICE.

HARRY H. BASSETT, OF FLINT, MICHIGAN.

DESIGN FOR A HEADLAMP BEZEL.

Application filed November 19, 1923. Serial No. 7,822. Term of patent 14 years.

To all whom it may concern:

Be it known that I, HARRY H. BASSETT, a citizen of the United States, and a resident of Flint, county of Genesee, and State of Michigan, have invented a new, original, and ornamental Design for Headlamp Bez-

In the drawing, Figure 1 is a front elevation of the head lamp bezel embodying my novel design, and Figure 2 is a top plan view thereof looking in direction of the arrows 2-2 in Figure 1.

I claim:

els, of which the following is a specifica- The ornamental design for a headlamp tion, reference being made to the accompany- bezel substantially as shown.

HARRY H. BASSETT.
